UNITED STATES PATENT OFFICE.

JOSEPH K. PRIEST, OF NASHUA, NEW HAMPSHIRE, ASSIGNOR TO AMERICAN SHEARER MANUFACTURING COMPANY, OF NASHUA, NEW HAMPSHIRE, A CORPORATION OF NEW HAMPSHIRE.

SHEARING AND CLIPPING DEVICE.

SPECIFICATION forming part of Letters Patent No. 743,190, dated November 3, 1903.

Application filed August 3, 1903. Serial No. 167,971. (No model.)

To all whom it may concern:

Be it known that I, JOSEPH K. PRIEST, a citizen of the United States, and a resident of Nashua, county of Hillsboro, State of New Hampshire, have invented certain new and useful Improvements in Shearing and Clipping Devices, of which the following is a specification.

My present invention relates to clipping and shearing devices, and is particularly applicable to hand-operated clippers.

This invention consists in providing means whereby the clipper may be operated by pressure of the hand perpendicularly of the surface being clipped; and it further consists in the construction, arrangement, and combination of the several parts comprising these means, substantially as hereinafter described, and specifically pointed out in the claims.

I have illustrated in the drawings a hand-clipper embodying one form of my invention, it being obvious that various changes in the arrangement and construction of the parts may be made without departing from the spirit of my invention.

In the drawings, Figure 1 is a plan view of a clipper embodying one form of my present invention; Fig. 2, a central longitudinal vertical section of same on line 2-2 of Fig. 1; Fig. 3, a vertical cross-section on line 3-3 of Fig. 1, and Fig. 4 a detail bottom plan of the lever end of the operating-handle.

Referring to the drawings, the handle 4 is made integral with a hollow casing 5. A comb-plate 6 is supported upon the bottom of the casing 5 by a bolt 7, which has a head 8, accommodated in a countersink at the lower end of an aperture in the comb-plate 6. The bolt 7 extends up through an aperture 9 in the top of casing 5 and is threaded upon its protruding upper end to receive a thumb-nut 10. A bent spring-washer 11 is disposed about the bolt 7 between the top of the casing 5 and the thumb-nut 10.

Two rigid studs 12 and 13 project downwardly from the casing 5 and are adapted to project through slots 14 and 15 in a top cutting-plate 16 and thence into nicely-fitting apertures 17 and 18 in the comb-plate 6 and act

in the threefold capacity of guides for the

movement of cutting-plate 16, stops for said movement, and lugs for preventing the rotation of comb-plate 6 to one side or the other about bolt 7.

The top cutting-plate 16 comprises a body 55 portion 19, provided on its front edge with cutting-teeth 20 and an extension 21 at its rear edge, substantially perpendicular to said body portion 19.

The body portion 19 of the cutting-plate 16 60 is adapted to lie upon the comb-plate 6, with its teeth 20 in operative registry with teeth 22 upon the forward edge of said comb-plate, and be guided thereon by the studs 12 and 13, as aforesaid. The upper surface of the 65 body portion 19 of the cutting-plate 16 is adapted to contact the under surface of the forward walls of the casing 5, which prevents upward movement of said cutting-plate. Tension is brought to bear on the cutting-plate 70 16 by screwing down thumb-nut 10 against spring-washer 11, which draws bolt 7, carrying comb-plate 6, upwardly, which causes comb-plate 6 to bind said cutting-plate 16 between its upper surface and the under surface 75 of casing 5 with any desired degree of tension.

The extension 21 of cutting-plate 16 is provided with an inclined slot 23, (see Fig. 3,) with which the inclined surfaces 24 of the forward end of a lever 25 engage.

The lever 25 is pivoted at 26 upon the casing 5 and has a rearwardly-extending handle portion 27, which lies directly beneath handle 4 and is designed to be grasped by the 85 fingers of the operator when handle 4 rests in his palm. Forwardly of the pivot 26 the lever 25 is provided with a slightly-elongated aperture 28, through which depends a guide-rod 29 from casing 5, which guide-rod prevents lateral shake of said lever. Forwardly of said aperture 28 in lever 25 is a larger elongated aperture 30, which accommodates bolt 7, being long enough to permit of the free working of lever 25 without contacting 90 said bolt.

A compressible spring 31 is disposed between the handles 4 and 27 and held in place by studs 32 on said handles.

It will be seen that the upward movement 100

of handle 27 by the fingers and its return by spring 31 will reciprocate the cutting-plate 16 through the medium of the mechanism described.

5. It is obvious that various changes may be made in the details of construction and arrangement without departing from the spirit of my invention.

What I claim as new, and desire to secure 10 by Letters Patent, is—

1. In shearing and clipping mechanism, the combination of a cutting member suitably mounted for movement in one plane and a lever member suitably mounted for movement

15 transversely of the direction of movement of said cutting member, one of said members being provided with a slot inclined to the direction of movement of both of said members and engaged by the other of said members.

20 2. In shearing and clipping mechanism, the combination of a cutting - plate suitably mounted for movement in one plane and having a slot directed transversely of its direction of movement and a lever engaging said 25 slot and mounted for movement in a plane transverse of said slot.

3. In shearing and clipping mechanism, the combination of a cutting - plate suitably mounted for movement in one plane and having a slot inclined relatively of its direction 30 of movement and a lever engaging said slot and mounted for movement in a plane transverse of said slot.

4. In shearing and clipping mechanism, the 35 combination of a cutting - plate suitably mounted for movement in one plane and having a slot directed transversely of the aforesaid plane, and a lever engaging said slot and mounted for movement in a plane transverse 40 of said first-mentioned plane and said slot.

5. In shearing and clipping mechanism, the combination of a cutting - plate suitably mounted for movement in one plane, and having a slot directed transversely of the aforesaid plane, and a lever having surfaces substantially parallel to and engaging the walls 45

of said slot, said lever mounted for movement in a plane transverse of said first-mentioned plane and said slot.

6. In shearing and clipping mechanism, the 50 combination of a cutting-plate mounted to move in one plane, consisting of a body portion having cutting-teeth and an extension substantially perpendicular to said body portion, said extension provided with a slot inclined to said body portion; and a lever engaging said slot and mounted to oscillate in a plane substantially perpendicular to said plane of movement of said cutting-plate.

7. In shearing and clipping mechanism, the 55 combination of a reciprocatable cutting-plate consisting of a body portion having cutting-teeth and an extension substantially perpendicular to said body portion and substantially parallel to the line of reciprocation of said 60 cutting-plate, said extension provided with a slot inclined to said line of reciprocation of said cutting-plate; and a lever engaging said slot and mounted to oscillate in a plane transverse of said line of reciprocation of said cutting-plate to reciprocate said cutting-plate.

8. In shearing and clipping mechanism the combination of a frame having a handle extending therefrom, a cutting-plate mounted to reciprocate upon said frame in a direction transverse of said handle, a lever pivoted upon said frame to oscillate in a plane transverse of the line of reciprocation of said cutting-plate, said lever having a handle portion disposed beneath the said handle of said frame; and an inclined slot and lug connection directly connecting said lever and said cutting-plate, whereby said cutting-plate is reciprocated by the oscillation of said lever.

In testimony whereof I have signed my 75 name to this specification in the presence of two subscribing witnesses.

JOSEPH K. PRIEST.
